CRATE FOR WATER BOTTLES OR ACID CARBOYS

Carl Eugene Johnson, Alhambra, Calif.

Application October 11, 1944, Serial No. 558,130

4 Claims. (Cl. 215—12)

1

This invention relates to crates for handling large glass bottles or acid carboys, whereby they may be transported and stored with the minimum risk of breakage. At present the crates employed for handling large glass bottles are constructed principally of wood, and the cost of repairing such crates constitutes an important factor in the sale and distribution of spring and distilled water.

The present invention has for its principal object the production of a novel and efficient crate constructed of light-weight metal which may be employed for handling large glass bottles or carboys, and is so designed as to withstand the transportation and storage roughing with less deterioration and at a lower cost.

A further object of the present invention is to provide a crate for an acid carboy, or other similar bottle or container, which crate includes means for holding a cover or hood over the acid bottle or carboy.

In the crate of the present invention, the carboy or bottle is held in a rectangular frame which includes four corner posts of channel formation with the channels positioned with the bases directly inwardly of the crate. To the bases of the channel posts are attached suitable buffering or cushioning material so that the corner posts hold the side contact surfaces of the crate, which contact surfaces engage the bottle or carboy to be received by the crate. The corner posts of the crate are so combined with the horizontal elements as to form handles by means of which the crate may be readily manipulated.

Associated with the crate proper, there is provided a retaining ring and cover-holding element detachable from the crate. This retaining ring is detachable for installing the bottle or carboy in the crate, and may later be reattached to assist in retaining the bottle in the crate, and includes means for holding the cover element enclosing the neck of the bottle.

The present invention will be most fully understood from the following description of a preferred form or example of the crate embodying the invention given in connection with the accompanying drawings, in which

Figure 1 is a plan view.

Figure 2 is a side-elevation.

Figure 3 is a horizontal section on the irregular line 3—3 of Fig. 2.

Figure 4 is a vertical section on the irregular line 4—4 of Fig. 1.

Figure 5 is an enlarged, fragmentary view, partly in section, of the upper end of one of the

2

corner posts with the horizontal member attached thereto.

Referring to the drawings, the crate comprises four corner posts 2 which are of channel form 5 and may be made of sheet metal, the bases of the channels being turned inwardly toward the axis of the crate and the channels being of sufficient depth so that the faces of the channels are at least as far inward and as near the axis of the 10 crate as any of the remaining portion of the crate. To the inside faces of the bases of the channels are attached buffer strips 3 of suitable cushioning material which are intended for contacting the side walls of the water bottles or carboys to be received by the crate. Near the top 15 of the posts a series of apertures 4 are provided in the bases of the posts, each base being indicated as being provided with three of the apertures 4. The apertures 4 serve as a means for 20 making detachable connections between the body of the crate and a metal retaining ring 5, as hereinafter more particularly pointed out.

The base of the crate is formed by a metal member 6, the body of which is in the form of a 25 flat, annular ring having an opening 7 of considerably smaller diameter than the diameter of the bottle to be received in the crate. The exterior of the flat body of the member 6 is of general square shape with channel openings cut 30 in the corners complementary to the cross-section of the channels of the post 2. On the base 6 is positioned a buffer ring 8 of suitable padding material which serves to receive the weight of the bottle or acid carboy. The base member 6 is 35 provided with upturned flanges 9a and 9b, which are beaded for stiffening purposes, as indicated at 10.

One flange 9a at one end, as viewed in Figure 3, is welded to the edge of the left-hand corner 40 post 2, extends hence to the right (its lower edge being joined to the base of the member 6) until it reaches the lower right-hand corner post 2 where it is welded to the edge thereof, then extends across said channel, as indicated at 14, 45 and is welded to the other edge of the corner post 2. The flange 9a then extends vertically, its lower edge joining the flat body of the member 6 until it reaches the upper right-hand corner post 2, as shown in Figure 3, where it is 50 welded to the edge thereof. The other flange member 9b is welded at one end to the upper right-hand corner post, as indicated, extends horizontally to the left, as indicated in Figure 3, being joined at its lower edge to the flat portion 55 of the base member 6 until it reaches the upper

left-hand corner post where it is welded to the edge thereof, extends across the channel of the post, as indicated at 14 welded to the other edge thereof, and then extends vertically downward, being joined at its lower edge to the base of the member 6 until it reaches the lower left-hand corner post 2 where it is welded to the edge thereof. In this manner it will be seen that two of the corner channels 2, i. e., the lower right-hand and upper left-hand channels, are bridged respectively by the section 14 of the flanges 9a and 9b while the intermediate channels are left open.

At the upper ends of the corner posts 2 there are provided horizontal members 12 and 13 of sheet metal, the lower edges of the members being turned up, as indicated at 14a, to provide a rounded surface.

The horizontal members 12 and 13 are complementary to the flanges 9a and 9b, and welded in a similar manner to the corner posts 2, portions 14b of the horizontal members 12 and 13 bridging the corner posts, as indicated in Figure 1. The two corner posts 2 which are not bridged by the flanges 9a and 9b of the base 6 are likewise left clear by the top horizontal members 12 and 13, whereas the intermediate corner posts 2 are bridged by these horizontal members. By this form of construction it will be seen that the portions 14b of the top horizontal members bridging the channel of the two diagonally opposite corner posts 2 and being rounded at their lower edges as shown at 14a serve as an excellent handle, by means of which the crate may be manipulated. In a similar manner, the portions 14 of the flanges 9a and 9b which bridge two of the diagonally opposite corner posts 2 serve as additional handles for the crate.

At the upper end of the crate there is provided a frusto-conical or slightly dome-shaped curved retaining ring 5 which is provided at its lower rim with four pins 15. Retaining ring 5 is sufficiently flexible so that the pins 15 are adapted to be selectively received in the apertures 4 in the corner posts and when so received the retaining ring 5 is attached to the frame of the crate. The series of apertures 4 on each corner post 2 provide a means for adjusting the height of the retaining ring 5 in order to accommodate bottles of different sizes.

The retaining ring 5 is provided with a plurality of pivoted clips 16 near the upper rim of the ring, which pivoted clips 16 are adapted to engage the lower rim of a metal cap 17 suitably shaped for enclosing the neck of a bottle or acid carboy received in the crate.

It has been found that the crate herein described may be very economically constructed and that it is greatly superior to the present wooden crate, particularly in that the rate of deterioration of the crate is very much less than that of the wooden crates. The crate of the present invention enables an important reduction in the cost of, as well as in the distribution of, liquids in large bottles, and also safeguards and protects the shipment in transit.

While the specific form of the crate herein described for the purpose of illustrating the invention is well adapted to carry out the objects of the present invention, it should be understood that various modifications and changes may be made, and this invention is of the scope of the appended claims.

I claim:

1. A crate for a bottle comprising a frame formed of metal and including four corner posts having bases and side portions arranged to form a channel-shaped section, the bases of the posts being turned towards the interior of the frame and adapted to serve as contact members for the bottle to be received by the crate, a base for said frame having flanged portions connected to said corner posts, upper horizontal members for said frame connected to said corner posts, said horizontal members bridging the side portions of two diagonally opposite corner posts to cooperate therewith in providing handles for manipulation of said crate.

2. A crate for a bottle comprising a frame formed of metal and including a base plate having upturned flanged portions, four corner posts having bases and side portions arranged to form a channel section, the bases of said posts being turned inwardly of the frame to serve as contact members for the bottle to be received by said crate, the flanged portions of the base being united to said posts, and upper horizontal members interconnecting said posts and bridging the side portions of two diagonally opposite posts to cooperate therewith in forming handles for said crate.

3. A crate for a bottle comprising a frame formed of metal and including a base and four corner posts secured to said base, said corner posts having bases with side portions arranged to form a channel section, with the bases of said posts turned inwardly of the frame so as to act as contact members, each of said corner posts having a plurality of vertically spaced apart openings near their upper ends formed in the base of each post, and a retaining ring having a detachable connection with such openings of said corner posts.

4. A crate for a bottle comprising a metal frame including a base member, four corner posts united to said base member, said corner posts having bases and side portions arranged to form a channel-shaped section, with the bases of the posts turned inwardly of the frame to provide contact-supporting members for the water bottle to be received by said frame, upper horizontal members interconnecting said posts, and a retaining ring having a plurality of extensions, and a plurality of apertures in said corner posts for providing detachable connections for said extensions of said retaining ring.
